UNITED STATES PATENT OFFICE.

CHARLES S. BURTON, OF OAK PARK, ILLINOIS.

TRACKER FOR AUTOMATIC MUSICAL INSTRUMENTS.

1,098,881.

Specification of Letters Patent. Patented June 2, 1914.

Application filed November 22, 1912. Serial No. 732,843.

To all whom it may concern:

Be it known that I, CHARLES S. BURTON, a citizen of the United States, residing at Oak Park, in the county of Cook and State of Illinois, have invented new and useful Improvements in Trackers for Automatic Musical Instruments, of which the following is a specification, reference being had to the accompanying drawings, forming a part thereof.

The purpose of this invention is to provide an improved tracker device for automatic musical instruments using perforated note sheets which shall be adapted for change of distance from center to center of the duct mouths to accommodate variations in the note sheets, either such as exists by reason of note sheets being cut upon different scales, and also such as result from changes in the sheet itself after cutting, from expansion and contraction due to atmospheric changes.

It consists in the elements and features of construction shown and described as indicated in the claims.

In the drawings:—Figure 1 is a front elevation of a tracker device embodying this invention, together with the note sheet rolls and associated parts. Fig. 2 is a section at the line 2—2 on Fig. 1. Fig. 3 is a section at the line 3—3 on Fig. 1. Fig. 4 is a view similar to Fig. 1, showing a modified form of the invention. Fig. 5 is a section at the line 5—5 on Fig. 4. Fig. 6 is an end elevation of the device of the form shown in Fig. 4.

The tracker device embodied in this invention comprises an assemblage of tubes, one for each tracker duct, arranged side by side in a row so as to present their mouths in the position of the tracker duct mouths in an ordinary tracker bar, such tubes being retained in such row by suitable guide and retaining bars, of which two bars between which the ends of the tubes are presented form the note sheet supporting surface or edge of the tracker. The tubes are spaced apart by tapering spacers, which being positioned at varying points of their length between the tubes, space the latter apart more or less, and so change the scale or uniform distance from center to center of the tubes, these spacers being substantially wedges of very slow taper and being all mounted on a single carrier so that they are advanced or retracted simultaneously and equally be-

tween the tubes for varying the distance from center to center of the tubes. The entire assemblage of tubes is pressed longitudinally by spring devices at the opposite ends, so that the wedge-like spacers upon being retracted permit the tubes to be pressed together by the springs, and upon being advanced between the tubes force the latter apart against the pressure of the springs. The middle spacer of the entire group is mounted upon the carrier so as to be immovable longitudinally of the group, and it thus serves to preserve the center of the entire row of tracker ducts unchanging; but all the remainder of the wedge-like spacers are loose on the carrier for movement on the carrier longitudinally of the latter and of the tracker ducts, and so that the tubes are spaced more or less by the greater or less intrusion of the wedge-like spacers between them, the spacers themselves are spaced on the carrier so that at all times they are in position to be advanced or retracted directly across the line of tubes between which they operate for spacing the latter.

The tubes, 1, as shown in the drawings, are square in cross section, and they are preferably parallel-sided for abutting flatwise against each other, or rather against the spacers in the row in which they are arranged to form the tracker. In order to afford ample space for connecting these tubes with flexible rubber tubes for leading to the pneumatic action in the usual manner, alternate tubes, 1, are bent to offset their rear end portions, 1^a, alternately to opposite sides of the planes of the axes of their forward or mouth portions, 1^b. Such offset is preferably effected by providing each tube with an oblique portion, 1^c, intermediate the end portions, 1^a, 1^b. These tubes are mounted between a middle supporting bar, 2, whose upper surfaces are sloped to fit the oblique trend of the portion, 1^c, of the tubes, and upper and lower supporting and retaining bars, 3, 3, whose lower and upper faces, respectively, are similarly sloped to correspond to the slope of the oblique portions, 1^c, of the tubes. The portions, 1^c, of the tubes project below the bars, 2 and 3, sufficiently to receive the flexible tubes, 4, for leading to the pneumatic action. The forward ends of the tubes are retained between parallel bars, 5, 5, whose forward surfaces flush with the forward ends of the tubes are slightly curved in the usual manner of the note-

sheet-supporting edge of ordinary tracker bars. All the bars, 2, 3 and 5, are organized into a rigid structure by means of end posts, 6, 6, to which the said bars are secured at 5 their opposite ends after the tubes are properly positioned between them, as shown in Fig. 2.

The bars, 5, 5, are spaced forward from the forward edges of the bars, 3, 3, to admit 10 between them the width of wedge-like spacers, 7. These spacers are preferably for convenience of operating the device's annular segments, though except as a matter of convenience in operation they might be 15 straight bars. At the thicker end, each of the spacers is formed with a hub whose thickness is nearly the normal distance from center to center of the tracker tubes at their closest spacing; that is to say, slightly less 20 than one-ninth of an inch. At their thinner ends, the spacers may be as thin as one-one-hundredth of an inch, increasing in thickness from the thinner ends back within a short distance of the hub at a very slow 25 taper, the maximum thickness at any point in the length designed to be entered between the tubes being not exceeding one-sixteenth of an inch, the difference in thickness between the thinnest and thickest portion 30 designed to be passed between the tubes being substantially the difference between the distance from center to center of the duct mouths of the tracker adapted to be operated with note sheets cut on the scale 35 of nine to the inch and slightly shrunken from that scale,—as such note sheets are liable to be in extremely dry weather,—and the distance from center to center of duct mouths of trackers adapted to be 40 operated with note sheets cut on the scale of six to the inch and slightly expanded, as such note sheets are liable to become in moist weather, the difference between the two scales being one-eighteenth of an inch, 45 and the total taper of the spacers being enough more than one-eighteenth of an inch to provide also for the shrinking and swelling of the note sheets. The middle spacer, 7^x, is mounted rigidly upon a shaft, 50 8, which is carried upon lever arms, 12, 12, of a rock shaft, 13, journaled in the end cheeks, 6, 6, said shaft, 8, extending parallel to the tracker at either side of the same, being shown above the tracker in the drawings. 55 The other spacers are mounted loosely on the same rock shaft so as to be free to slide thereon. The said middle spacer, by its rigidity with the rock shaft, is adapted to keep the center row of the tracker ducts 60 unchanged through all adjustments, and to further insure this result against the liability of the spacer, 7^x, to be sprung laterally on account of its thinness, it is further guided and positioned by spring clips, 9, 9, 65 which are mounted on the upper and lower

bars, 3, so as to clasp the spacer, 7^x, between their spring fingers, their elasticity permitting them to spread to accommodate the taper of the spacer, but their stiffness being adapted to effectively resist the slight 70 tendency to deflection of the spacer laterally, which would change the center of the row of tracker ducts. The rock shaft, 13, is journaled as stated, in the end posts, 6, with its axis substantially in the plane of the 75 axes of the mouth portions, 1^b, of the tubes, 1; that is to say, it is directly back of the row of tracker duct mouths; and the wedge-like spacers as mounted on the shaft, 8, and guided between the upper edges of the 80 bar, 3, and the lower edges of the bar, 5, are curved about the axis of the rock shaft, 13, so that the rocking of the shaft, 13, causes the spacers to be thrust or drawn in the paths in which they lie back and forth 85 between their said guides and between the tubes which they space apart.

The rock shaft, 13, is provided with an operating handle, 14, by which it may be rocked to swing the shaft, 8, and thrust or 90 draw the spacers, 7, 7^x, through between the tubes, 1, for varying the spacing apart of the latter. For pressing the tubes together and against the spacers, there are mounted between the bars, 3, and the bars, 5, at each 95 end of the entire group of tubes and spacers, follower blocks, 15, backed by springs, 16, which in turn are backed by bars, 17, which extend across the tracker protruding above and below the same. If the device were 100 designed only for adjusting the tubes to accommodate their spacing to the expansion and contraction of the note sheets due to atmospheric changes, the springs, 16, by their resiliency would accomplish the purpose 105 without provision for any other movement of the follower blocks, 15; but the movement for following up the tubes through the changes of position necessary for adjusting the entire group from a spacing of substantially 110 one-sixth of an inch in to the position resulting from spacing them at one-ninth of an inch, is more than can be provided for by resiliency of springs which can be accommodated in the space which it is 115 desirable to allow for such springs. For that reason, the cross bars, 17, instead of being mounted fixedly to afford backing for the springs, are mounted so as to be moved longitudinally of the tracker substantially 120 the full distance necessary for accommodating the change of longitudinal dimension of the tracker from that necessary for eighty-eight (or whatever number of ducts constitute the entire tracker) ducts spaced at one-sixth of an inch to that necessary for the same eighty-eight ducts spaced at one-ninth of an inch; and for moving the entire spring 125 cushions comprising each the follower block, 15, backing block or cross bar, 17, and inter- 130

posed springs, 16, longitudinally in and out along the length of the tracker, there are mounted on the outer sides of the cheeks, 6, respectively, transverse rock shafts, 18, 18, having at each end lever arms, 19, 19, extending forward nearly to the forward edge of the bars, 3, 3, and connected by pitman links, 20, 20, with the opposite ends of the cross bars or backing blocks, 17, which are provided with bracket lugs, 17^a, extending from their rear edges for pivotal connection of said pitman links. It will be seen that by rocking the shafts, 18, the spring cushions comprising the parts, 15, 16 and 17, will be caused to slide along the tracker toward and from the middle. Of course, such movement inward can be made only as the wedge-like spacers are withdrawn from between the tubes to permit the latter to be closed up, and such movement outward will be desired only as the spacers are thrust between the tubes to spread them more widely; and the movement of the spring cushion should, therefore, in the main correspond to the position of the spacers;—that is, the depths to which they are thrust through between the tubes; but it will be seen that the springs, 16, will accommodate a very considerable amount of inaccuracy in the relative adjustment of the spring cushions as a whole and the spacers. For causing the position of the spring cushions to approximately correspond to the adjustment of the spacers, the rock shaft, 18, is provided at each end,—that is, outside each post, 6,—with a bevel gear, 22, and these bevel gears mesh with bevel gears, 23, 23, on the rock shafts, 18, 18, respectively, causing the latter to be rocked equally and oppositely with the rocking of the shaft, 13. The parts are proportioned so that the angular movement of the rock shaft, 13, necessary for the movement of the spacers throughout their whole range of adjustment is substantially the same as the angular movement of the lever arms, 19, and necessary for sliding the spring cushions the entire distance necessary for corresponding adjustment; and the bevel gears, 22, on the shafts, 13, are therefore shown equal to the bevel gears, 23, on the shafts, 18.

In Figs. 4, 5 and 6, a modification of this invention is shown, consisting in its application to a form of tracker device in which the tracker ducts are in staggered arrangement in two parallel rows at the mouth edge of the tracker, as is desirable, especially for use in a player mechanism having two sets of key-actuating mechanisms which are to be controlled through the medium of separate sets of tracker ducts. In this modification, there are two rows of tracker tubes, 1^x and 1^y, the tubes of one row being opposite the spaces between the tubes of the other row. The two rows are spaced apart by a spacing bar, 5^y, and are held against said spacing

bar at their forward ends by parallel outside guide bars, 5^x, corresponding to the bars, 5, of the first described form. The tubes of both sets are further guided and held in place by guide and retaining bars, 3^x, 3^y, 70 positioned at a distance back from the bars corresponding to the retaining bars, 3, of the first-described construction. The spacing bar, 5^y, extends in width so as to be opposed to the bars, 3^x, as well as to the bars, 5^x. All the bars, 5^x, 5^y, 5^y, and 3^x, 3^y, are connected at their ends to end posts, 6^x, forming with said posts a rigid frame structure in which the tubes are held and guided. Preferably, for stopping the tubes against endwise movement, they are each provided on their outer surfaces on the side toward the bars, 5^x and 3^x, with stops, m, which are merely little pieces of metal soldered on to the sides of the tubes which are engaged back of the bars, 5^x, and in front of the bars, 3^x, as seen in Fig. 5. In the end posts, 6^x, there are journaled shafts, 8^x; which are square between their bearings and have mounted upon them for rotation with them, 90 but with freedom for lateral movement on them, spacers which are in the form of disks, 7^x, circular in outline, having square apertures for mounting them on the shafts for rotation and lateral movement as described. 95 These disks are wedge-shaped in diametric section in one direction, so that they taper circumferentially from one side around to the opposite side, in whichever direction the circumference is followed from the thinnest 100 point. The disks are mounted on the shafts with their thinnest points all alined at the same side of the shaft. The disks are of such diameter that those upon each shaft intrude between the tubes of the row at the 105 same side of the spacing bar, 5^y. In addition to the spacers, 7^x, which intrude between the consecutive disks of the respective rows, there is mounted upon each of the square shafts at the one end of the proximate row of tubes an outside spacer or follower disk, 7^x, whose outer surface is in a plane at right angles to the axis and which fills out the interval between the last tube of said proximate row and the vertical plane 110 of the outer surface of the last tube at the corresponding end of the other row; that is, so that said outer surface of the spacer or follower disk, 7^x, is in the same vertical plane 115 as the outer surface of said last tube of said other row. Hung on the two shafts by means of collars, 30, exteriorly circular and having square openings for fitting the shaft, there is pivoted at each end of the system of tubes a follower consisting each of a cross bar or 120 follower block, 15^x, and a backing block, 17^x, and interposed springs, 16^x, coiled around the shafts respectively, these followers constituting means of closing up the rows or tubes so as to hold them in close arrangement. 130

ment to whatever degree they may be spaced by the adjustment of the circumferentially tapered spacers, 7^x, as the shafts, 8^x, are rotated to move the disks in the direction of their taper between the tubes. For so rotating the two shafts and insuring their equal rotation, they are provided with pinions, 33, 33, which mesh with a gear segment, 34, on a rock shaft, 13^x, journaled in the posts, 6^x.
 10 On each end of the shaft, 13^x, there is a bevel gear, 22^x, which meshes with bevel gears, 23^x, on transverse rock shafts, 18^x, journaled in brackets carried by the posts, 6^x, said transverse shafts having lever arms, 19^x, connected by links, 20^x, with the opposite ends of the bars, 17^x, for operating the spring cushion followers simultaneously and correspondingly with the spacers, 7^x, for closing up and permitting the extension in length of 20 the rows of tubes, as required in view of the change in their spacing caused by the rotation of the spacer disks, 7^x, the action in this respect being in all respects similar to that shown and described in the form shown in 25 Figs. 1, 2 and 3.

I claim:—

1. A tracker device for automatic musical instruments comprising a set of tracker duct tubes assembled laterally in a row; means 30 by which they are retained in the row; tapering spacers interposed between consecutive tubes, and means for supporting and moving the spacers between the tubes to vary the distance apart of the latter.

35 2. A tracker device for automatic musical instruments comprising a set of tracker duct tubes assembled laterally in a row; means by which they are retained in the row; tapering spacers interposed between consecutive tubes; a carrier on which the spacers are assembled with freedom of lateral movement thereon, and means for moving the carrier to move the spacers between the tubes for varying the distance apart of the latter.

45 3. A tracker device for automatic musical instruments comprising a set of tracker duct tubes assembled laterally in a row; means by which they are retained in the row; tapering spacers interposed between consecutive tubes; a rocking carrier on which the spacers are mounted with freedom of lateral movement thereon, and means for rocking the carrier to move the spacers between the tubes to vary the distance apart of the latter.

55 4. A tracker device for automatic musical instruments comprising a set of tracker duct tubes assembled laterally in a row; means by which they are retained in the row; tapering spacers interposed between consecutive tubes; a rocking carrier on which the spacers are mounted for rocking therewith with freedom of lateral movement thereon, and means for rocking the carrier to move the spacers between the tubes.

65 5. A tracker device for automatic musical

instruments comprising a set of tracker duct tubes assembled laterally in a row; means by which they are retained in the row; tapering spacers interposed between consecutive tubes; followers at the ends of the row 70 of tubes; means for moving the spacers between the tubes to vary the distance apart of the latter, and connections from said means for moving the followers lengthwise of the row of tubes for accommodating the 75 change of length of the row due to change of spacing.

6. A tracker device for automatic musical instruments comprising a set of tracker duct tubes assembled laterally in a row; means 80 by which they are retained in the row; tapering spacers interposed between consecutive tubes; elastically yielding followers at the opposite ends of the row of tubes for 85 intervening spacers, and means for moving the spacers between the tubes to vary their distance apart.

7. A tracker device for automatic musical instruments comprising a set of tracker duct 90 tubes assembled laterally in a row; means by which they are retained in the row; tapering spacers interposed between consecutive tubes; elastically yielding followers at the opposite ends of the row of tubes for 95 holding them pressed together against the intervening spacers; means for moving the spacers between the tubes to vary their distance apart, and connections from said 100 means to the followers for moving them correspondingly toward and from each other.

8. A tracker device for automatic musical instruments comprising a set of tracker duct tubes assembled laterally in a row; longitudinal guide bars by which they are retained in the row; tapering spacers interposed between consecutive tubes, and means for supporting and moving the spacers between the tubes to vary the distance apart 105 of the latter.

9. A tracker device for automatic musical instruments comprising a set of tracker duct tubes assembled laterally in a row; means by which they are retained in the row; tapering spacers interposed between consecutive tubes; means for supporting and mounting the spacers comprising a rock shaft extending longitudinally of the row, and a shaft actuated thereby on which the spacers are mounted with freedom of lateral movement thereon, and means for rocking the rock shaft.

10. A tracker device for automatic musical instruments comprising a set of tracker duct tubes assembled laterally in a row; means by which they are retained in the row; tapering spacers interposed between consecutive tubes; a carrier on which the spacers are mounted with freedom of lateral movement thereon, said carrier comprising 115

110

115

120

125

130

- a rock shaft extending longitudinally of the row, and a bar on which the spacers are mounted, the spacers being curved about the axis of the rock shaft, and means for rocking the shaft. 5
11. A tracker device for automatic musical instruments comprising a set of tracker duct tubes assembled laterally in a row; means by which they are retained in the row; tapering spacers interposed between consecutive tubes; a longitudinal rock shaft; a shaft on which the spacers are mounted, and connections by which the rock shaft actuates the spacer-carrying shaft; followers at the opposite ends of the row of tubes mounted for movement toward and from each other for holding the tubes and intervening spacers in close arrangement; transverse rock shafts and connections therefrom for moving the followers, and gear connections from the longitudinal rock shaft to said transverse rock shafts, and means for rocking one of said shafts. 10
12. A tracker device for automatic musical instruments comprising a set of tracker duct tubes assembled laterally in a row; means by which they are retained in the row; tapering spacers interposed between consecutive tubes; a longitudinal rock shaft; lever arms on said rock shaft at the opposite ends of the row of tubes; a bar carried by said lever arms for supporting the spacers; followers at the opposite ends of the row of tubes mounted for movement toward and from each other for holding the tubes and intervening spacers in close arrangement; transverse rock shafts and connections therefrom for moving the followers, and gear connections from the longitudinal rock shaft to said transverse rock shafts, and means for rocking one of said shafts. 15
13. A tracker device for automatic musical instruments comprising a set of tracker duct tubes assembled laterally in a row; means by which they are retained in the row; tapering spacers interposed between consecutive tubes; a carrier on which the spacers are mounted with freedom of lateral movement thereon, said carrier comprising a rock shaft extending longitudinally of the row, and a shaft or bar on which the spacers are mounted, the spacers being curved in the arcs of circles about the axis of the rock shaft, and means for guiding them between the tubes in the paths in which they are thus curved. 20
14. A tracker device for automatic musical instruments comprising a set of tracker duct tubes assembled laterally in a row; means by which they are retained in the row; tapering spacers interposed between consecutive tubes; a carrier on which the spacers are mounted with freedom of lateral movement thereon, said carrier comprising a rock shaft extending longitudinally of the row, and a shaft or bar on which the spacers are mounted, the spacers being curved in the arcs of circles about the axis of the rock shaft, and means for rocking the rock shaft. 25
15. A tracker device for automatic musical instruments comprising a set of tracker duct tubes assembled laterally in a row; means by which they are retained in the row; tapering spacers interposed between consecutive tubes; means for moving the spacers to vary the distance apart of the tubes, said tubes being bent to offset their rear end portions alternately in opposite directions from the longitudinal plane containing the axes of their forward portions, and a bar interposed between their oppositely deflected portions against which the tubes are lodged at the hip formed by such deflection. 30
16. A tracker device for automatic musical instruments comprising a row of tubes assembled laterally with their mouths all in the same plane; guide bars between which their forward portions are thus assembled with freedom of lateral movement; tapering spacers interposed between the tubes, and means for moving the spacers to vary the distance apart of the tubes, said tubes being bent alternately in opposite directions to offset their rear portions from the longitudinal plane containing the axes of their forward portions; a guide bar interposed between their oppositely deflected portions extending longitudinally of the row, and having the tubes lodged upon it at the hip formed by said deflection, and longitudinal guide bars outside said deflected portions between which and said interposed bars their said deflected portions are retained and guided in the lateral movement of the tubes. 35
17. A tracker device for automatic musical instruments comprising a set of tracker duct tubes assembled laterally in a row; means by which they are retained in the row; tapering spacers interposed between consecutive tubes; a carrier on which the spacers are assembled and adapted to be moved between the tubes, one of said spacers being fixed against lateral movement on said carrier and the remainder being movable laterally thereon, and means for holding the tubes in close arrangement against their intervening spacers. 40
18. A tracker device for automatic musical instruments comprising a set of tracker duct tubes assembled laterally in a row; means by which they are retained in the row; tapering spacers interposed between consecutive tubes; a carrier on which the spacers are assembled and adapted to be moved between the tubes, one of said spacers being fixed against lateral movement on said carrier and the remainder being movable laterally thereon, and a yielding follower at the end of the row. 45

19. A tracker device for automatic musical instruments comprising a set of tracker duct tubes assembled laterally in a row; means by which they are retained in the row; tapering spacers interposed between consecutive tubes; a carrier on which the spacers are assembled and adapted to be moved between the tubes, one of said spacers being fixed against lateral movement on said carrier and the remainder being movable laterally thereon; a follower at the end of the row;

means for moving the spacers between the tubes, and connected means for moving the follower.

In testimony whereof, I have hereunto set 15 my hand at Chicago, Illinois, this 16th day of November, 1912.

CHARLES S. BURTON.
